UNITED STATES PATENT OFFICE.

VICTOR LEE EMERSON, OF PHILADELPHIA, PENNSYLVANIA.

BOILER OR STILL.

1,365,777.

Specification of Letters Patent. Patented Jan. 18, 1921.

Application filed December 11, 1919. Serial No. 344,087.

To all whom it may concern:

Be it known that I, VICTOR LEE EMERSON, a citizen of the United States, and a resident of Philadelphia, in the county of Philadelphia and State of Pennsylvania, have invented certain new and useful Improvements in Boilers or Stills, of which the following is a specification.

The adaptation of boilers or stills to the distillation of petroleum is made difficult by the high temperatures and pressures prevailing. In order to properly distil the petroleum oils, a temperature in excess of 750° F. is required, which is accompanied by a very high pressure. It follows that satisfactory apparatus cannot be adapted from the designs developed for water boilers, and it is essential that the peculiar conditions of temperature and pressure be considered in the design of a boiler.

The elevated temperatures cause an abnormal expansion of the boiler parts and will result in leakage at the joints unless special provision is made to withstand strains and distortions. The high pressures will likewise require special provision in the design.

It is an object of my invention to provide a boiler or still which is well adapted for the distillation of petroleum oils. The number of joints is reduced to the minimum, and facility exists for an appreciable expansion of the parts in response to the considerable temperature changes.

It is a further object of my invention to render easy the cleaning of the boiler pipes and their replacement when worn out.

It is a still further object of my invention to provide a still in which the material is given a uniform heating and caused to circulate freely.

Further advantages will be evident from the specification which follows and the drawings which form a part thereof.

In the drawings:—

Figure 1 shows a vertical section of a still embodying my invention;

Fig. 2 is a horizontal section on the line 2—2 of Fig. 1; and

Fig. 3 is a horizontal section on the line 3—3 of Fig. 1.

One form of still such as contemplated in my invention is illustrated in the drawings and consists of two connected headers, one of which forms a vapor dome and outlet. A plurality of circulating tubes connect the

two headers and pass through the heating zone of a furnace. The lower header 4 is mounted upon a brickwork foundation 5 which is channeled as at 6 to provide ready access to the bottom of the header for cleaning. The bottom of the header consists in the main of a closure plate 7 which is bolted securely to the wall of the header and provides against leakage. The sides of the header taper inward as at 8 and are pierced to receive the ends of the circulating pipes. The upper edge of the tapering walls 8 is bolted to a vertical pipe 9, axially located with respect to the header 4. An upper header 10 is provided with a plurality of cylindrical members 11 and 12. The lower cylindrical member 12 rests upon a support 13 and has inwardly tapering walls 14 by which it is bolted or otherwise fastened to the pipe 9. The upper cylindrical portion 11 of the header is flanged for engagement with the corresponding flange on the upper edge of the member 12 slightly above the support 13 and for a purpose hereinafter to be described. The upper member 11 is of considerable height and its top includes a plate 15 which carries an outlet 16 by which the vapors from the still may be carried off.

Connecting the tapering wall 14 of the upper header with the correspondingly tapering wall 8 of the lower header is a plurality of circulating pipes 17. These pipes are curved outward, and adapted to be seated in apertures of the plates 8 and 14. The flanges of the parts 11 and 12 of the upper header are so arranged that it is possible to remove the upper member 11 and to insert a curved pipe 17 through the hole in the upper plate 14 and into the corresponding hole in the plate 8. The pipe may then be fastened by bolting, welding, or other analogous operation. The pipes 17 are arranged in concentric circles and slightly spaced each from the other.

The support 13 for the upper header rests upon a masonry or other foundation 18 to which it is held by the circular metal ring 19. The foundation 18 is generally circular and provides vertical walls 20 resting upon the ground or floor. The walls 20 are concentric with and spaced from the wall 5 supporting the lower header. One side wall of the foundation 18 carries a flue 21 leading from a furnace 22. The flue 21 leads through an opening in the vertical series of pipes 17 and delivers the heated gases to a

100

circular compartment 23. This compartment 23 is formed by the annular wall 24 and the lining 25 surrounding the pipe 9. The wall 24 and the lining 25 meet at the 5 base of the pipe 9 and extend upward for the greater length of the said pipe. The wall and lining are supported on the foundation walls 5 and 20. The wall 24 together with the wall 18 establishes a channel extending 10 downward to the circular chamber between the wall 5 and the wall 20 which leads to an outlet 26 and thence to a chimney.

After the boiler or still has been charged with the material to be distilled, the heated 15 gases from the furnace will rise through the flue 21 and circulate between the lining 25 and the wall 24 in a whirl. The heated gases then pass upward and circulate uniformly around the upper portions of the curved 20 pipes 17. The gases are then diverted downward in the direction of the pipes to the chamber between the walls 5 and 20, thence through outlet 26 to the chimney.

The heat from the gases will pass primarily to the chamber around the central pipe 9, thence in contact with the upper portions of the curved pipes 17 and finally throughout the remaining length of the 25 pipes.

In this way all portions of the still between the two headers will be subjected to varying degrees of heat. The material such as petroleum to be distilled will be readily affected; setting up convection currents 30 which will maintain a circulation in the following direction: upward in the curved pipes 17, and downward through the return pipe 9. Any solid material will be segregated from the current in the lower header 35 4, and may be removed as convenient. The vapors from the fluid in the lower header and curved pipes will have a ready passage up the latter and into the upper header, from whence they can be drawn off. The 40 initial contact between the hottest gases and the fluid occurs in the upper region of the still. This aids the ready distillation of the volatile portions of the latter.

The lining 25, surrounding the pipe 9 for 50 the lower part of its length, serves to shield the pipe from the effects of the incoming gases. The wall deflects the gases and causes them to whirl around the pipe and deliver their heat first to its upper portion. There 55 will be, therefore, the minimum of retardation to the fluid passing down the pipe.

It will be evident that the curved pipes

are held only at their ends and that there is ample space for their expansion horizontally. Furthermore, by the removal of the 60 upper portion 11 of the header 10 it will be possible to insert cleaning means into the pipes or if necessary withdraw individual pipes for replacement or repair.

The arrangement of headers vertically 65 and the application of heat first to the upper portions creates most favorable conditions for vaporization. As both headers are fixedly mounted on the supporting base, full advantage is taken of the ability of the 70 curved pipes to accommodate themselves to strain and protect the joints against leakage.

It is found of material advantage to construct the upper header capable of the removal of its upper section. The size of the 75 upper section may be varied to insure the quick withdrawal of volatile products free from priming.

What I claim as my invention is:

1. A boiler or still comprising an upper 80 header and a lower header, a central vertical pipe therebetween, a plurality of curved tubes connecting the headers, and a wall between said pipe and tubes forming a heating chamber adapted to direct products of 85 combustion upwardly against the upper end of said tubes.

2. A boiler or still comprising an upper header and a lower header, a central vertical pipe therebetween, a plurality of curved 90 tubes connecting the headers, a heating compartment between the pipe and tubes, said compartment having an outlet at the upper ends of the said tubes.

3. A boiler or still comprising an upper 95 header and a lower header, a central vertical pipe therebetween, a plurality of curved tubes connecting the headers, a heating compartment between the pipe and the tubes, said compartment having an outlet at the 10 upper ends of the said tubes, and a flue leading into the compartment.

4. A boiler or still comprising an upper header and a lower header, a central vertical pipe therebetween, a plurality of curved 10 tubes connecting the headers, a walled heating compartment between the pipe and tubes, said compartment having an outlet at its upper end, a flue leading into the compartment, and a chimney flue leading from 11 the lower ends of said tubes.

In testimony whereof, I have hereunto set my hand.

VICTOR LEE EMERSON.
